United States Patent Office.

HAMILTON STICKNEY, OF RENO, PENNSYLVANIA.

Letters Patent No. 71,421, dated November 26, 1867.

COOKING-STOVES.

The Schedule referred to in these Letters Patent and making part of the same.

TO ALL WHOM IT MAY CONCERN:

Be it known that I, H. STICKNEY, of Reno, in the county of Venango, and State of Pennsylvania, have invented a new and useful Improvement in Cooking-Stoves; and I do hereby declare that the following is a full, clear, and exact description thereof, which will enable others skilled in the art to make and use the same, reference being had to the accompanying drawings, forming part of this specification.

This invention relates to a new and improved construction and combination of parts, whereby I am enabled to adapt the base-burning principle to cooking-stoves; and the invention consists in arranging a base-burning furnace, and by suitable flues conducting the products of combustion to where the heat can be utilized for cooking and other domestic purposes, as will be hereinafter more fully described. The drawing,

Figure 1, represents a vertical sectional elevation of the stove through the line *xx* of fig. 2, showing the arrangement of the furnace and flues and the air-passages.

Figure 2 is a horizontal sectional view through the line *yy* of fig. 1.

Similar letters of reference indicate like parts.

The cooking-stove proper is represented by A, with the supply-chamber in the centre, marked B. C is the hearth of the stove. The stove-grate is conical in form, and is marked D. This grate is supported by a conical frame, marked D', which is itself supported by the upper portion of the ash-box B'. There is an ash-pan, A', which slides under the grate upon the hearth, and air is admitted to the fuel through sliding dampers over the ash-pan. With the exception of that portion of the stove which forms the hearth, and which portion is open, the furnace is surrounded by a casing which is composed of circular slides, by which an oven, C', is formed around the furnace, access to which is obtained by the slides before mentioned. One of the slides is seen at *a*. The bottom of the oven is marked *c*. *b* is a grate or rack in the oven. Provision is made for the admission of air by holes through the slides, as seen at *d*, which air passes up through the oven, and into the air-passage *e'*. The smoke and products of combustion pass from the furnace upward through a flue, marked *f*.

The flues and passages for both smoke and air are formed of concentric cylinders, as represented in the drawings; consequently the flues are annular in form, or in their cross-section, and extend from the upper plate, or surface of the stove, to the bread-oven, which is marked E.

The arrangement for boiling, or the ordinary kettle-holes of the cooking-stove, are through the plate F. The products of combustion are brought in direct contact with the kettles, and may be made to pass to the outer edge of the stove, and from thence into the flue *f'*, under the top plate F, between the holes, and then be conducted upward through the flue *f*, or they may pass directly upward into the vertical flues *f*, as indicated by the arrow at *e*. In the former case the current is controlled by the damper *g*, in the latter by an annular-ring damper, which is operated by the projecting lever *h*. Air is admitted into the air-passage *i i* from the lower oven *a*, and also from above the plate F, as seen at *J*. Heated air may be conducted directly into the upper oven E, and it is controlled by suitable dampers, so that it may be discharged into the room, if desired, through apertures marked *k*.

In the bread-oven E there are revolving shelves marked *m m*, which are supported by pivots *n n*. These shelves are perforated with holes, and they are connected together by vertical rods, and thereby to a spider, *o*, which is supported by the upper pivot *n*. P is the door, through which the fuel is introduced into the furnace. The fuel burns only at the base, or on the grate, from whence it ascends, as already described. The pot or boiler-holes through the top of the stove are seen in fig. 2, marked S.

What I claim as new, and desire to secure by Letters Patent, is—

1. The construction of the oven C', formed by the circular slides *a* around the furnace, as herein described, for the purpose specified.
2. The stove A, constructed as described, and provided with the air-openings *e'*, forming a communication from the oven C', through said furnace, to the annular flues *i* and bread-oven E, as herein described, for the purpose specified.
3. I claim the flues *ff'*, and the air-passages *J i i*, and the revolving shelves *m m*, in the elevated oven E, arranged relatively to the fuel-supply chamber B, and operating substantially as shown and described.

HAMILTON STICKNEY.
